ABSTRACT

An electrically rotated half wave plate comprised of four electrically varied obstacle planes, consisting of respective sets of varactor diodes, spaced 45° apart in a circular waveguide propagating circularly polarized microwave energy. The four sets of varactor diodes are synchronously driven in a manner to cause the resultant or effective obstacle plane to continuously rotate between 0° and 360° within the waveguide in response to control voltage inputs applied to the four sets of varactor diodes.

MICROWAVE PHASE SHIFTER

BACKGROUND OF THE INVENTION

1. Field of the Invention

This invention relates generally to phase shifters of electromagnetic energy and more particularly to an electrically controlled phase shifter having birefringent properties.

2. Description of the Prior Art

In microwave signal processing systems, a requirement exists for a phase shifting device capable of introducing continuous phase changes at rates producing frequency offsets in the low megahertz (MHz) range without degrading the spectral purity of the microwave signal being processed in the general frequency range of 50Hz-50KHz from the central spectral line. What is generally desired is to produce a linear phase versus time function extending over hundreds of wavelengths in times the order of 100 microseconds to an accuracy of $\pm 3^\circ$.

Continuously variable phase changers by means of which the phase of an output wave is shifted with respect to the input wave are well known components in the art of microwave transmission. One such phase changer consists of a mechanically rotated half wave plate coupled between two quarter wave plates which act as polarization converters wherein linearly polarized waves are first converted to circularly polarized waves, applied to the rotating half wave section and then reconverted to linearly polarized waves with the instantaneous phase shift introduced being dependent on the instantaneous angular relationship of a thin slab of dielectric material relative to a fixed reference established by the input polarization converter. Such apparatus is shown and described in detail in U.S. Pat. No. 2,858,512 issued to E.F. Barnett.

A magnetically controlled ferrite phase shifter is furthermore disclosed in U.S. Pat. No. 2,787,765. A.G. Fox wherein an electrically controlled rotating magnetic field is applied to a ferromagnetic material in the presence of the magnetic field is utilized for varying the angular relationship of the applied field to the polarization of the wave energy for varying the phase shift in the manner previously described but removing the limitations imposed by mechanically moving parts.

To achieve this function by use of a microwave digital phase shifter requires a six bit unit with one-half least significant bit accuracy at all phase states capable of switching between each state in the order of 3/5 nanoseconds (10^{-9} seconds) including settling time to within one-half least significant bit at a peak switching rate in the order of 200MHz.

Still other past attempts to accomplish this type of function have been limited to much lower phase shift rates and employed combination of digital phase shifting and serrodyne frequency offsetting using traveling wave tubes.

SUMMARY

Briefly, the present invention is directed to an improved phase shifter of the type including a half wave plate operable upon circularly polarized waves wherein the angular relationship of a shunt susceptance obstacle plane relative to a fixed reference is electrically controlled and rotated by means of the operation of four sets of varactor diodes (voltage variable capacitors) mounted inside of a circular waveguide and being

spaced every 45° therein and covering a span of 120° . The four varactor sets are synchronously driven by cyclically varying, e.g., sinusoidal control signals such that the first and third sets have signals applied which are 180° out of phase with one another as does the second and fourth sets; however, a phase difference of 90° exists between adjacent sets. Thus four variable shunt susceptances having a 90° relative phase shift between adjacent susceptances are provided inside of the waveguide. Each varactor diode set, moreover, comprises at least one but preferably a plurality of equally spaced varactor diodes aligned in a linear fashion extending longitudinally within the waveguide and substantially parallel to the central axis thereof.

BRIEF DESCRIPTION OF THE DRAWINGS

FIG. 1 is a perspective view generally illustrative of a typical prior art rotary phase shifter utilizing a mechanically rotated half wave plate;

FIG. 1a is a perspective view further illustrative of a prior art half wave plate including a dielectric element;

FIG. 2 is an axial cross sectional view of the preferred embodiment of the subject invention;

FIG. 3 is a partial longitudinal sectional view further illustrative of the preferred embodiment of the subject invention shown in FIG. 2;

FIG. 4 is a diagram illustrative of the cyclic capacitance/susceptance variation of the four varactor sets being illustrative of operation of the embodiment shown in FIGS. 2 and 3; and

FIG. 5 is a diagram illustrative of the driver control voltage signal pattern applied to the four sets of varactor diodes.

DESCRIPTION OF THE PREFERRED EMBODIMENT

Prior to discussing the preferred embodiments of the subject invention, it is desirable to give further discussion to prior art apparatus which is diagrammatically illustrated in FIGS. 1 and 2, in order to provide a better understanding of the subject invention when it is subsequently considered in connection with FIGS. 2 and 3. Referring now to FIG. 1, a mechanically rotatable phase shifter is basically comprised of a rotatable half wave plate 10 located between input and output transitions to circular waveguide which typically converts TE_{10} rectangular mode waves to the TE_{11} mode and quarter wave plates 12 and 14, respectively, which converts the linearly polarized TE_{11} mode waves into a circularly polarized TE_{11} mode waves and vice versa. Reference numerals 16 and 18 refer to the input and output rectangular waveguide section for coupling linearly polarized waves to and from the phase shifter. Intermediate the input rectangular waveguide section and the first quarter wave plate 12 is the rectangular to circular waveguide transition section 20. Similarly, a second waveguide transition section 22 couples the quarter wave plate 14 to the output rectangular waveguide section 18.

The quarter wave plate sections 12 and 14 are characterized by circular waveguide members having respective obstacle planes 21 and 23 comprised of dielectric slabs positioned 45° with respect to rectangular side walls of the rectangular waveguide. If for example the thin slab of dielectric material were placed parallel to the electric field E of an incident linearly polarized electro-magnetic wave propagating the waveguide, the wave would experience a maximum velocity of retarda-

tion. The least velocity of retardation would occur when the incident electromagnetic wave has its electric field E perpendicular to the dielectric material. Accordingly, when the incident electric field E , which in a rectangular waveguide such as shown in FIG. 1 exists in a plane parallel to the short walls, intersects the 45° plane of the dielectric slab in the quarter wave plate section 12 two component vectors E_1 and E_2 will emerge with a 90° differential phase shift such as shown in FIG. 1a. It can be shown that this emergent wave may be regarded as a circularly polarized electric wave. Therefore, a linearly polarized electric wave is changed to a circularly polarized electric wave by traveling through the quarter wave plate section 12. Similarly, if a circularly polarized wave is passed through the quarter wave plate section 14, it emerges with a linear polarization having an axis of polarization dependent upon the sense of rotation of the incident circularly polarized wave coming from the half wave plate 10.

The rotary half wave plate 10 is additionally shown in FIG. 1a and typically consists of a section of circular waveguide 24 having a slab 26 of dielectric material of a length L axially mounted across the diameter of the waveguide. Considering that a linearly polarized electric field E is converted to a polarized wave consisting of two components E_1 and E_2 at right angles to one another, the diagram in FIG. 1a illustrates the condition where the electric field vector E_1 is perpendicular to the slab 26 while the field vector E_2 lies in the plane of the slab. As noted above, the electric field vector E_1 will experience a minimum retardation while the field E_2 will experience a maximum retardation. Thus, the propagation constant β_1 for the field vector E_1 is greater than the propagation constant β_2 for the field vector E_2 in the slab 26. Passing of the electric field vectors E_1 and E_2 through the circular waveguide 24 having a dielectric slab 26 of a length L can be expressed as:

$$E_1 \text{ out} = E_1 \text{ in } e^{-j\beta_1 L} \text{ and}$$

$$E_2 \text{ out} = E_2 \text{ in } e^{-j\beta_2 L}$$

Accordingly, the length L of the dielectric slab 26 is chosen to obtain a differential phase change, $\beta_1 L - \beta_2 L = 180^\circ$.

Thus, if a circular polarized electric wave is introduced into a section of waveguide such as shown in FIG. 1a, it emerges with circular polarization in an opposite sense, i.e., from a clockwise to a counter clockwise sense. Further, if the circular waveguide 24 containing the slab 26 is physically rotated by an angle ϕ relative to a fixed reference such as that provided by the dielectric 21 in the input quarter wave plate section 12 shown in FIG. 1, the emergent circular wave from the circular waveguide 24 will have its phase shifted through an angle 2ϕ . Further, the passage of the emergent circularly polarized wave from the half wave plate through the output quarter wave plate 14 shown in FIG. 1 converts the circular polarized wave back into a linearly polarized wave shifted in phase relative to the input linearly polarized wave. It can be seen, therefore, that the continuous rotation of the rotatable half wave plate 10 shown in FIG. 1 will provide a smooth continuous phase variation of 0° to 360° for each 1/2 revolution of the waveguide 24. Due to the unavoidable imperfection in the manufacture of waveguide components, a rotary phase shift additionally normally includes means 28 and 30 in the waveguide transitions 20 and 22 to ab-

sorb the small amount of improperly polarized energy present therein. Typically, these may comprise horizontally oriented film loads. The absorption of improperly polarized energy effects energy loss but not forward phase shift. Also when desirable, the dielectric slab elements may be contoured to minimize reflections.

While the operating principle of the rotary phase shifter is well documented, for example in the above referenced prior art, one may also refer to the treatment given to such devices in the text entitled *Foundations for Microwave Engineering*, Robert E. Collin, McGraw-Hill, 1966 at pages 265-270, inclusive.

The same class of device can be designed for operation in connection with coaxial or other TEM mode transmission systems by the use of transitions to rectangular waveguide or by direct launching of circularly polarized waves in circular guides from the coaxial line employing a helical coupler, thus eliminating the need for quarter wave plates. The rotary half wave plate, however, still is necessary component.

Proceeding now to the inventive concept contemplated by the subject invention, the inherent mechanical limitation in the rotation rate at which the phase can be varied is overcome by effecting an electrical rotation of the half wave plate member, thereby realizing phase scanning rates in the megahertz (MHz) range. While the aforementioned Fox patent obtains electrical rotation by generating a rotating magnetic field around a ferrite element and thus provides one means for obtaining fast scanning rates, the present invention is directed to still an improved control phase shifter having birefringent properties, i.e., producing 180° differential phase shift along two orthogonal principal axes. Accordingly, the present invention is directed to a controlled varactor half wave plate, the preferred embodiment of which is shown in FIGS. 2 and 3. Directing attention now to the preferred embodiment, four sets 32, 34, 36 and 38 of linearly aligned varactor diodes (voltage variable capacitance diodes) are mounted inside of a section of circular waveguide 40 such that the four sets of varactor diodes are adapted to form four obstacle planes 33, 35, 37 and 39 spaced 45° apart inside of the waveguide. The four sets of varactor diodes are identical in construction and number and are axially oriented within the waveguide 40 and operate as variable shunt susceptances across the waveguide when respectively operated by suitably applied electrical control voltages.

Considering one set of varactor diodes for example the second set 34 as an illustrative example and shown in FIG. 3, a plurality of varactor diodes 42₁, 42₂ . . . 42_n have one like electrode terminating in a longitudinally extending metal member 44 which may be, for example, a pin or a rod which is attached to but insulated from the waveguide 40 by stand-off elements 43 and 45. A DC return element 46 moreover is either connected to the circular waveguide 40 which would be grounded or would be connected back to a ground return lead 48 associated with a varactor voltage control driver circuit 50. The other like electrode of the plurality of varactor diodes 42₁ . . . 42_n are probe coupled out of the waveguide 40 and commonly connect to a bias control voltage supplied by the driver circuit 50. Varactor diode set 32, for example, would be connected to the driver circuit 50 by means of a common circuit lead 52 while varactor sets 34, 36 and 38 would be connected back to the driver circuit 50 by means of

common circuit leads 54, 56 and 58.

Each plurality (n) of varactor diodes forms $N = n-1$ sections providing a length L . The varactor diodes, moreover, are desirably spaced apart one quarter wavelength ($\lambda/4$) of the mean operating frequency of the microwave energy propagated through the waveguide 40. The plurality of varactor diodes may consist of equal susceptances or be configured to exhibit a "taper" wherein the first and last susceptance 42₁ and 42_n have one half the value of the intermediate susceptances. This can easily be accomplished by proper selection of the diodes themselves or in any other known fashion such as by paralleling diodes. Also the same result can be effected by suitable biasing techniques well known to those skilled in the art. It has also been observed that an odd number of sections ($N = 3$ to 7) provide the best operating characteristic.

In operation, it is desired that the varactor capacitances be selectively varied generally as shown by the diagram in FIG. 4. It can be observed that alternate sets of diodes operate as opposing pairs of susceptances with a 90° shift between adjacent sets. By applying time related, e.g., sinusoidal control voltages such as shown in FIG. 5, the susceptance pattern is varied substantially as shown by FIG. 4 resulting in an effective or resultant obstacle plane 60 corresponding to the dielectric plate 26 shown in FIG. 2 which rotates within the waveguide 40. Moreover, where for example the control voltages applied to the varactor diode sets vary sinusoidally the effective obstacle plane 60 will exhibit a rotation angle ϕ of 180° for each cycle of the applied control voltage. Since a 2 ϕ phase shift is provided in a half wave plate, each complete cycle of the synchronized varactor control voltages appearing on circuit leads 52, 54, 56 and 58 will provide 360° of phase shift for a circularly polarized wave propagated through the circular waveguide 40.

It will be observed that the control voltages applied to the first and third set of varactor diodes 32 and 36 are 180° out of phase with respect to one another. The same may be said for the control voltages applied to the third and fourth set of varactor diodes 34 and 38. A simplification in the drive circuit connection to the varactor diodes immediately becomes evident by considering varactor diode sets 46 and 36 operated as mutually opposite pairs and varactor diode sets 34 and 38 operated as a second mutually opposite pair. By selectively choosing one set of diodes in each pair to have inverse characteristics or simply by inverting their connections, sets 46 and 36 can be commonly driven by a first control signal from a driver circuit 50 while the second pair of diodes 34 and 38 can be driven by a second control signal 90° out of phase with respect to the first.

The apparatus thus described comprises a microwave analog phase shifter which provides the capability for smooth and continuous phase change over a 360° range by 90° phase shifted variation of control voltage inputs applied to four cumulative shunt susceptances spaced 45° in a circular waveguide. It should also be pointed out that a digital processor employing control data stored in programmable semiconductor memories in conjunction with available integrated circuit digital to analog convertors can also be used to obtain the desired phase control. The present invention, moreover, is inherently a molulo 2π phase shifter requiring no reset since the control inputs for 360° are identical to those for 0° and since a unique combination of a con-

trol voltage input corresponds to each phase angle between 0° and 360°.

Having thus described what is a present considered to be the preferred embodiment of the subject invention, I claim:

1. A microwave phase shifter, comprising in combination:

a section of circular waveguide adapted to propagate circularly polarized waves therein;

at least four electrically controlled variable capacitance means, adapted to respectively operate as shunt susceptances, in said waveguide section being located at substantially the same longitudinal position intermediate the central axis and the inner wall surface of the waveguide and further being spaced substantially 45° apart in a plane transverse to the central axis; and

electrical circuit means coupling respective mutually synchronized control signals to said at least four variable capacitance means for selectively varying the capacitance value thereof and providing a varying resultant shunt susceptibility therefrom which generates an effective rotatable obstacle plane for said circularly polarized waves, thereby imparting a phase shift thereto which is a function of the angle of said obstacle plane relative to a fixed reference.

2. The microwave phase shifter as defined by claim 1 wherein said electrical circuit means coupling respective mutually synchronized control signals to said four variable capacitance means comprises circuit means generating four sinusoidal control voltages consecutively phased 90° apart, and wherein said four control voltages are respectively applied to said four variable capacitance means.

3. The microwave phase shifter as defined by claim 1 wherein said at least four electrically controlled variable capacitance means comprises four sets of axially aligned varactor diodes and wherein said electrical circuit means coupling control signal to said four sets of varactor diode means comprises circuit means for varying the capacitance of each set of diodes in cyclic fashion such that the variation between adjacent varactor diode sets is shifted 90°.

4. The phase shifter as defined by claim 1 and additionally including microwave circuit means coupled to one side of said circular waveguide section for coupling circularly polarized waves thereto; and

second microwave circuit means coupled to the opposite side of said circular waveguide section for coupling circularly polarized waves therefrom.

5. The phase shifter as defined by claim 1 wherein said at least four electrically controlled variable capacitance means each comprises respective sets of varactor diode means.

6. The phase shifter as defined by claim 5 wherein each set of varactor diode means comprises a plurality of spaced apart varactor diodes linearly aligned along the longitudinal direction of said circular waveguide section.

7. The phase shifter as defined by claim 6 wherein said plurality of varactor diodes are substantially equally spaced and providing $N = n-1$ sections where n is the number of the varactor diodes utilized.

8. The microwave phase shifter as defined by claim 7 wherein N is equal to an odd number.

9. The microwave phase shifter as defined by claim 8 wherein N is an odd number including the numbers 3 and 7.

10. The microwave phase shifter as defined by claim 1 and additionally including first microwave circuit means coupled to one side of said circular waveguide section for converting linearly polarized waves to circularly polarized waves; and

second microwave circuit means coupled to the other side of said circular waveguide section for converting circularly polarized waves to linearly polarized waves.

11. The phase shifter as defined by claim 10 wherein said first and second microwave circuit means comprises quarter wave plate microwave circuit means.

12. The microwave phase shifter as defined by claim 11 wherein both quarter wave plate microwave circuit means includes a circular waveguide portion; and additionally including first and second waveguide transition elements respectively coupled to the first quarter wave plate microwave circuit means for providing a transition from rectangular waveguide to circular waveguide, and to said second quarter

10

15

20

wave plate circuit means for providing a transition from circular waveguide to rectangular waveguide.

13. The microwave phase shifter as defined by claim 11 wherein said at least four electrically controlled variable capacitance means each comprises a set of spaced apart axially aligned varactor diodes electrically connected together in respective parallel circuit relationship.

14. The microwave phase shifter as defined by claim 12 and wherein said electrical circuit means coupling respective mutually synchronized control signals to said four sets of varactor diodes comprises circuit means coupling a like cyclically variable control signal to each set of varactor diodes with each control signal being phased 90° apart such that the first and third set of varactor diodes receive a first pair of signals 180° apart and wherein said second and fourth set of varactor diodes receive a second pair of signals 180° apart.
